(57) **CLAIM**

The ornamental design for a can, as shown and described.

DESCRIPTION

FIG. 1 shows a perspective view of my design for a can;
FIG. 2 shows a side elevational view of my design for a can;
FIG. 3 shows a top plan view of my design for a can; and,
FIG. 4 shows a bottom plan view of my design for a can.
The broken lines shown are included for the purpose of illustrating portions of the can that form no part of the claim.
